Attorney

UNITED STATES PATENT OFFICE.

CHARLES B. JUDD, OF COUNCIL BLUFFS, IOWA.

VOLTAIC BELT.

SPECIFICATION forming part of Letters Patent No. 366,777, dated July 19, 1887

Application filed August 26, 1886. Serial No. 211,951. (No model.)

To all whom it may concern:

Be it known that I, CHARLES B. JUDD, a citizen of the United States, residing at Council Bluffs, in the county of Pottawattamie and State of Iowa, have invented a new and useful Improvement in Voltaic Belts, of which the following is a specification.

My invention relates to certain improvements in voltaic belts.

10 The object of my invention is to couple the plates together compactly, to secure an increased quantity and strength of current, and to form a flexible chain without the employment of hinge-joint connections between the 15 plates, each set of plates being easily removed from the string and replaced thereon, or placed at varying distances from each other, to permit the plates to be conveniently cleaned or renewed by unskilled persons, and to provide 20 ample space around the plates for free circulation of air and to prevent polarization.

The improvement consists in various constructions and combinations of parts herein-after specified, and particularly designated in 25 the claims, with reference to the accompanying drawings, wherein—

Figure 1 is a side elevation of my improved belt; Fig. 2, a plan of the same; Fig. 3, a perspective of the end of the belt enlarged, showing the abutment-plate for holding the plates upon the string; Fig. 4, an elevation of a short section of plates which may be used separately or connected to other similar sections. Fig. 5 represents a view of an adjustable connection 30 by which the electrodes may be adjusted to any portion of the belt to vary the current. Fig. 6 represents a perspective view of one of the tubular conductors which are interposed between the voltaic elements of the belt, and 35 Fig. 7 an enlarged view of one end of the insulating-string and its threading attachment.

The preferred form of my invention is shown in the first three figures of the drawings, wherein rectangular strips of zinc, A, and corresponding strips of copper, B, are placed upon opposite sides of a strip, C, of felt cloth or other absorbent material, to form a single cell or group of plates, each strip being correspondingly perforated at its ends a a', to receive an insulated string or wire, D, which serves to hold the plates together. Between

each group of plates I preferably interpose a metal cylinder, E, of conducting material, also strung upon the insulated string D, which serves to hold the plates apart in separate cell-groups with intervening spaces located between each group to allow free circulation of air, and thus accelerate evaporation, and also provide ample space between the plates to permit them to be easily cleaned without being removed from the string, and to prevent polarization by separating the cells from each other a sufficient distance.

The insulated string D is preferably doubled, one end thereof being passed through the holes a upon one end of the strips or plates, and the other end thereof passed in the same direction through the other ends of said strips or plates. The string is then drawn tightly from its ends to bind the plates together closely in contact with each other, and the ends of said string are then laced through perforations f in an abutment-plate, F. (Shown clearly in Fig. 3 of the drawings.)

The plate F may be slipped or adjusted upon the string D, to retain the plates A B thereon with any required tightness, the elasticity of the felt layers or strips C being sufficient to render the chain more or less flexible at all times.

The string D is preferably formed of a copper wire, d, and a tubular rubber cover, d', which latter forms a complete insulation between the plates A and B, and is perfectly non-corrosive. The string D may be made of rubber solely or of other material covered with rubber, and the ends of said string are tipped with metal points d', which permit the plates to be easily threaded.

A short section of plates is shown in Fig. 4. The terminal copper plate B at one end of said section is provided with a hook, B', and the abutment-plate F of said section is formed with a slot or eye, F', to receive the hook of an adjoining and corresponding section of plates. By this means a chain of any required length and strength of current may be formed, and short sections may be used separately for special purposes requiring a current of less intensity.

Acidulated water, vinegar, or other electrolytic fluid is employed to moisten the felt strips

and generate the current, and the chain may be inclosed in any well-known or preferred form of jacket, H', to protect the body from the fluid or moistened felt strips.

- 5 The conductors L, provided with electrodes L' at one end and contact-plates L² at the opposite end, may be attached to the terminal plates of the battery, or the conductor may be attached to any one of the intermediate plates 10 of the chain, thus shortening up the circuit and decreasing the strength of the current. This object is effected by making the electrodes bifurcated at l l', as shown in Fig. 5 in detail, the members being made of spring metal, so 15 as to embrace any desired plate and form electrical connection therewith, communication with the next adjoining plate or opposite element being prevented by the interposed felt, thus preventing short-circuiting.
- 20 When the belt is worn, the electrodes L' are applied to the body at separate points in any desired position, according to the portions desired to be subjected to the action of the electric current. It is evident that when thus applied 25 the portions of the body between the electrodes form part of the electric circuit, thus compelling the current to take its course through the body or a particular portion thereof.
- 30 By the above-described arrangement of plates a current of great intensity may be obtained from a short flat belt, which may be

closely encircled upon the extremities, or inclosed within a small compass, and sufficient space is left between the plates for cleansing 35 them easily and for preventing polarization.

A number of separate zinc plates may be placed one upon the other, as shown in Figs. 4, 7, 8, and 9, to re-enforce and replace each other as they become consumed, and unskilled 40 persons may easily unstring the plates to clean or replace the old plates with new ones.

I claim as my invention and desire to secure by Letters Patent—

1. A voltaic belt consisting of cell-groups 45 of positive and negative plates, with layers of absorbent material placed between them, the tubular conductors located between the respective groups, and the strings passing through the groups and the tubular conductors to bind 50 the whole together and form a flexible chain, substantially as specified.

2. The combination, in a voltaic belt, of the plates A B, absorbent layer C, conducting sleeves E, and strings D, with the terminal 55 plates F, having perforations f, through which the ends of the strings are laced, whereby the cell-groups are secured together, substantially as specified.

CHARLES B. JUDD.
